TWO-STROKE ENGINE

Emile Claveau, Paris, France; vested in the Alien
Property Custodian

Application November 19, 1941, Serial No. 419,783

4 Claims. (Cl. 123—65)

A type of two-stroke engine is known in which the admission under pressure of fresh gases and the exhaust of burnt gases take place by means of ports which lie one above another. The engine piston successively uncovers and covers the said ports during a part of its up- and down-strokes in the neighbourhood of its lower dead centre. The drawback of engines of this kind is that the admission and exhaust ports remain simultaneously open during a short time so that a portion of the fresh gases passes directly out through the exhaust ports.

This invention relates to a two-stroke engine in which this drawback is avoided. This engine is chiefly characterized by the fact that a movable obturating ring which is broad enough for covering the exhaust ports and which is in contact with the inner face of the cylinder is brought by the piston in front of the exhaust ports during the admission period of fresh gases, while this obturating ring is drawn away by the piston from its position in front of the exhaust ports during the exhaust period. For this purpose, the piston is, for instance, provided with an upper extension comprising a groove, and with openings which connect the inside of the cylinder, during the down-stroke of the piston, successively with the exhaust ports and then with the admission ports. The obturating ring which is continuously maintained applied against the inner wall of the cylinder by its elasticity is alternately displaced, in a reciprocating motion, with intermediate intervals of rest, by the upper edge and then by the lower edge of the piston groove in which the said ring is set and the height of which is larger than the height of the said ring.

Thus the movable obturating ring acts in co-operation with the piston as a slide valve by means of which the inside of the cylinder is successively connected with the exhaust ports and then with the admission ports, the exhaust ports being closed during the period of admission.

Several embodiments of the invention are shown by way of non limitative examples in the appended drawings. In these drawings:

Figure 1 is a diagrammatical axial sectional view of the engine which is supposed to be a single-cylinder engine.

Figures 2 to 6 are diagrammatical views of the cylinder and of the piston of the engine on a larger scale and in different positions of the piston.

Figure 7 is a cross-sectional view of the piston and of the cylinder of the engine at the exhaust port level in the case of Figure 2.

Figures 8 to 11 are diagrammatical views of the cylinder and of the piston of the engine of a second form thereof, in positions corresponding to those of Figures 2 to 6, respectively;

Figures 12 to 15 are diagrammatical views of the cylinder and of the piston of the engine of a third form thereof, in positions corresponding to those of Figures 2 to 6, respectively;

Figures 16 to 19 are diagrammatical views of the cylinder and of the piston of the engine of a fourth form thereof, in positions corresponding to those of Figures 2 to 6, respectively;

Figure 20 is a fragmentary longitudinal sectional view through a modified form of slide valve, and

Figure 21 is a fragmentary longitudinal sectional view through another modified form of slide valve.

In the form of execution in which it is shown in the drawings the engine comprises a cylinder 1 inside of which a piston 2 can move, which piston is connected by a connecting rod 3 and a crank 4 to the engine shaft 5.

The piston 2 comprises a recessed bottom 2' which forms a kind of head the walls of which are provided with one or more openings 6, 6a (Figures 2 and 7). It comprises furthermore, on its external face, an annular recess 7 in which a slideable ring valve 8 is located, the height of the said ring valve being less than the height of the recess.

The said ring is split and has a certain elasticity so that it always remains applied against the inner wall of the cylinder.

9 and 10 are the exhaust and admission ports respectively, bored in the cylinder 1.

In its upper part the latter is closed by an ordinary threaded plug 11 screwed into a tapped hole and to which the ignition member (not shown) is secured.

Finally, 12 are packing rings provided in the piston 2.

The operation is as follows:

When the piston 2 is at its lower dead centre (Figure 2) the admission ports 10 are uncovered while the exhaust ports 9 are covered by the slide ring valve 8.

The admission of the explosive mixture into the cylinder takes place at this moment through one of the usual means used for two-stroke engines. Owing to the fact that the exhaust ports are covered by the slide ring valve 8, the admission and exhaust pipings cannot communicate in any way.

55 The piston begins its up-stroke.

When it has effected a stroke which is equal to the height of the admission ports 10 it has covered the latter (Figure 3) and on pursuing its up-stroke it carries along with it (by means of the lower edge of the recess 7) the slide ring valve 8 which had remained pressed by its elasticity against the cylinder wall in front of the exhaust ports.

The stroke of the piston continues up to its upper dead centre, the admission and exhaust ports remaining covered and the compression of the explosive mixture continuing.

When the piston 2 is about to reach its upper dead centre (Figure 4) the explosion takes place and the piston begins its down-stroke. Shortly after the beginning of the latter, the upper edge of the recess 7 of the piston (position shown by dotted lines) draws along in a downward direction the slide ring valve 8 which had remained during this time pressed against the cylinder wall due to its elasticity and to the pressure of the cylinder gases on its internal face.

The down-stroke or expansion stroke of the piston goes on until the exhaust ports 9 are uncovered (Figure 5); then the burnt gases pass rapidly through the openings 6 of the piston and escape almost instantaneously through the said exhaust ports 9. Then, these exhaust ports are very rapidly covered by the slide ring valve 8 (Figure 6) and the admission ports 10 are about to be uncovered by the piston 2 and will be completely uncovered when the piston reaches its lower dead centre (Figure 2). Fresh gases enter the cylinder through the said admission ports 10 and through the openings 6 of the piston under the action of any known admission means used in two-stroke engines, this admission being promoted by the vacuum obtained in the cylinder by the perfect obturation of the exhaust ports by the slide ring valve 8.

And so on.

In the form of execution shown in Figures 8 to 11 the ring 8 has a height which is substantially equal to the distance between an admission and an exhaust port.

In the form of execution shown in Figures 12 to 15 the ring 8 is high enough to project beyond the recess 7. It is drawn along by an inner collar 8a with which its lower part is provided. With this arrangement it is possible to ensure a substantial overlapping of the exhaust ports 9 by the slide ring valve 8.

In the case of Figures 16 to 19 the slide ring valve is provided with two inner drawing collars 8a and 8b.

Operating conditions in the case of the three above mentioned embodiments are the same as those shown in Figures 1 to 7.

Figures 20 and 21 show an elevational view with a partial sectional view of a portion of a slide valve 8 made of thin metal and provided with grooves such as 8c in which a graphitic paste 8d is placed which ensures a good lubrication of the slide valve ring.

If desired, any shock absorber such as springs, thin corrugated blades, gas cushion with a vent or the like can be inserted between the ring 8 and the upper and lower edges of the recess 7.

I claim:

1. A two stroke engine comprising a cylinder, a piston, an exhaust port and an admission port located in the inner surface of the cylinder, these ports being successively covered and uncovered

by the piston, a ring sliding in the cylinder and cooperating with the said exhaust port, said ring being in frictional contact with the cylinder to such degree as to hold the ring against sliding to enable the piston to have a sliding movement relatively thereto and independently thereof, a head protruding from the upper part of the piston and formed with an annular outer recess provided with openings facing the exhaust and admission ports and with two transverse surfaces capable of engaging the sliding ring to move the ring to a limited extent with the piston and located at such a distance apart from each other that when the piston uncovers the admission port the exhaust port is covered by the sliding ring and that, after the piston has covered the admission port, it covers the exhaust port and carries away with it the sliding ring.

2. A two stroke engine comprising a cylinder, a piston, an exhaust port for the exhaustion of burnt gases out of the cylinder, and an admission port for the admission of a fresh explosive gaseous charge into the cylinder, these ports cooperating with the piston for the exhaustion of the burnt gases and for the admission of the fresh explosive charge, and an elastic sliding ring expanding into contact with the inner surface of the cylinder to such degree as to hold the ring against sliding to enable the ring to have a sliding movement relatively thereto and independently thereof, said ring being large enough to cover the exhaust port and means carried by the piston to move the said ring through abutment therewith in front of the admission port and cover it when the inlet port is uncovered.

3. A two stroke engine comprising a cylinder laterally provided with an exhaust port and an admission port, an explosion chamber, a piston provided with an outer annular recess and cooperating with the said exhaust and admission ports for the exhaustion and the admission of the motive gases of the engine, the said annular recess matching with both the exhaust and admission ports when the piston approaches the end of its outer stroke, conduits leading through the piston from the inside of the said annular recess to the cylinder explosion chamber, an expanding ring in frictional contact with the inner wall of the cylinder to such degree as to hold the ring against sliding to enable the ring to have a sliding movement relatively thereto and independently thereof, said ring being broad enough to close the outlet port, an upper abutment carried by the annular recess and capable of engaging with the sliding ring and of driving it to a position for which it covers the exhaust port before the piston uncovers the admission port, a lower abutment carried by the annular recess and capable of engaging with the sliding ring after the piston has covered the admission port and driving the said annular ring together with the piston.

4. A two stroke engine comprising an exhaust and an admission port, a piston cooperating with the said ports for controlling the exhaust and admission of the gases of the engine and a sliding ring provided with an outer annular recess containing a lubricating pasty medium, and cooperating with the said ports and with the piston to keep the exhaust port covered during the time the admission port is uncovered and until the piston has covered the exhaust port.

EMILE CLAVEAU.
